UNITED STATES PATENT OFFICE.

HENRY JOHN CULLUM, OF LONDON, ENGLAND.

GRAMOPHONE.

Application filed January 6, 1925. Serial No. 897, and in Great Britain February 21, 1924.

This invention refers to improvements in or relating to gramophones and like sound-reproducing machines and it has for its primary object to provide a portable machine of improved and simplified construction and which, whilst being of extremely small overall dimensions, is capable of playing records of large or small sizes.

Now according to the present invention in a portable gramophone or like sound-reproducing machine, I arrange the turntable so that it can be slid or otherwise moved in a horizontal plane in relation to the tone arm in order to render it possible to play records of larger size.

In order that the present invention may be clearly understood and more readily carried into effect, it is hereinafter described with reference to the accompanying drawings, in which:

Figure 1 is a plan view of a portable gramophone constructed in accordance with the present invention, the said view showing the case opened and the motorboard and turntable in position for playing records of small size;

Figure 2 is a substantially similar view to Figure 1 but showing the motor, motor-board and turntable slid horizontally out towards the front of the case to enable records of larger size to be played;

Figure 3 is a substantially similar view to Figure 1 illustrating an arrangement in which the turntable is turned radially about a fixed pivot point;

Figure 4 is a similar view to Figure 3 illustrating an arrangement in which the motor and turntable are guided in parallel slots in the motor-board.

In carrying the present invention into effect, the motor *a* and turntable *b* are mounted in a suitable case or container *c* having a hinged lid *d* and provided with the usual carrying handle *e*. The tone-arm is mounted on a hinged platform *g* arranged over one end of a sound amplifying chamber *h* adapted to direct the sound waves in an upward direction. The platform *g* is hinged at *g'* and adapted to be maintained in its raised or horizontal position when the machine is in use by means of a spring-controlled stay (not shown), and it is limited as regards its upward movement by means of suitable screws or stops *i* provided at the sides of the amplifying chamber *h*. The tone-arm is mounted on the hinged platform *g* so that

it is capable of being turned about a vertical axis in a horizontal plane, and it is itself formed in two sections *f*, *f'* and provided in its length with a hinge or joint *j* giving an angular movement about a horizontal axis, thus permitting the sound-box *k* to be turned up out of engagement with the record. The articulated sections *f*, *f'* of the tone-arm are in

screwed engagement with each other but they are prevented from complete disengagement by the off-set arrangement of the sound box *k* which prevents the one part *f'*

being completely rotated on the other part *f*. The tone-arm *f*, *f'* is of taper construction

and is connected directly by a lateral flange *f²* at its end *f'* to the metal back plate *l* of the sound box *k*, the connection itself being

made by means of screws *m* passing through radial slots (not shown) in the flange *f²* on

the end of the tone-arm *f'* and engaging the metal back plate *l* of the sound box *k*. Thus

by loosening the screws *m* a certain amount of relative rotary movement between the end

of the tone-arm *f'* and the sound-box *k* is

provided for, thus allowing the angular relationship of the needle to the disc to be ad-

justed at will. For storage purposes, the hinged platform *g* is adapted to be lowered by pushing in the spring-controlled stay,

when the platform will fall down about its rear hinged end *g'* so that the tone-arm *f*, *f'*

with the sound box, when suitably folded will be entirely accommodated within the

sound amplifying chamber *h*. The lower

portion or wall of this chamber may if de-

sired be provided with a dent or depression (not shown) adapted to accommodate the lower bent portion of the tone-arm and to

prevent same from movement when the lid *d* of the case *c* is closed. On its diaphragm

or stylus side, the sound-box *k* is provided with a cover-plate *n* having a central socket-

piece *o* and a suitable slot therethrough (not

shown) for the passage of the stylus arm. The socket-piece *o* on the side of the cover

plate *n* is provided for engagement with a

small bent auxiliary amplifying horn *p* which is adapted to be secured thereto so as

to increase the volume of sound and make up

for the otherwise small dimensions of the

apparatus, being say 7 inches in diameter,

but the spacing and shape of the tone arm

f, *f'* are such that 10 inch records can be

played, the larger sized records overhanging

the turntable.

In order to render it possible to play a

still greater range of records the motor *a* and the turntable *b* may be slidably or adjustably mounted in the case. To this end means may be provided for keeping the turntable *b* in its correct position during transit. In the construction shown in Figures 1 and 2, the motor board *q* is mounted on slides *r* on the box *c* and is held frictionally in place by the provision of metal bars *r'* on the box *c* which grip the side edges of the motor board at the top. The movement of the turntable is therefore a forward one, as shown in Figure 2, but it may if desired be a lateral or sideways movement, as indicated for instance in dotted lines *q'*. In this case, however, the slides *r* would be arranged lengthwise of the box *c*. In the modified construction shown in Figure 3, the motor *a*, turntable *b* and motor-board *q* are arranged to swing upon a pivotal centre *s* which may be formed by the shoulder or seating of the time indicator plate. This fitment permits of the motor *a*, the turntable *b* and the motor-board *q* being pushed over radially away from or towards the centre of the motor portion of the cabinet, so that the centre spindle of the motor is in or about the centre of the motor box or container when the machine is not being used. In the construction shown in Figure 4, the motor *a* and turntable *b* move in guide slots *t* in the motor-board *q*, the movement being away from the vertical pivot point of the tone arm as will be readily understood. In all cases, the arrangement is such that the winding spindle of the motor comes opposite to a winding key hole *d* in the case *c* when it is in its winding position. The sound chamber *h* may be placed at the right-hand side of the machine, as shown, or the left-hand side of the machine by reversing the position of the motor and the direction of the motor movement, or at the back of the machine. The motor may then when pushed over into its central position rest in a convenient position with the turntable *b* or the motor board *q* overlapping the sound chamber, but giv-

ing just sufficient room for the tone-arm *f f'* to lodge alongside or underneath the turn-table edge. The lid of the box or container shown in Figures 1 and 2 comprises a strongly made framework of the same size as the bottom container which is hinged at *d''* in the usual lid fashion to the back of the case *c*.

What I claim is:—

1. In a portable gramophone, a turn table, a tone arm, a means to permit adjustment of the turn table relative to the tone arm, said means permitting the turn table to remain in any position of adjustment during the playing of a record.

2. In a portable gramophone, a casing, a tone arm mounted therein, a turn table, a means for supporting the turn table in the casing to permit bodily movement of the turn table relative to the tone arm, said turn table supporting means permitting the turn table to be held in any of its positions relative to the tone arm during the playing of a record.

3. In a portable gramophone, a casing, a motor board therein, a motor carried by the motor board, a turn table carried by the motor board, means for movably supporting the motor board to permit it to be moved together with the turn table relative to the tone arm.

4. In a portable gramophone, a casing, a tone arm carried thereby, and a turn table mounted for bodily slidable movement in the casing to adjust the turn table relative to the tone arm.

5. In a portable gramophone, a casing, a tone arm carried thereby, a motor board, a motor carried by the motor board, a turn table carried by the motor board, and means for mounting the motor board in the casing to permit sliding movement of said board with the motor and turn table to thereby adjust the turn table relative to the tone arm.

In testimony whereof I have hereunto signed my name.

HENRY JOHN CULLUM.
